CARPET.

No. 17,775.

Patented Oct. 11, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,775, dated October 11, 1887.

Application filed September 8, 1887. Serial No. 240,191. Term of Patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is divided up into separate panels or parts by means of a partial stem-work, rows of small ornamental figures, and other ornamental lines, which serve to mark off the different panels from one another. In the spaces 20 between the panels are conventional flower forms, large and small, and a variety of orna-

mental forms partly geometrical in character. The panels themselves are of different sizes and irregular outlines, being bounded in part 25 by short right lines perpendicular to each other, forming a block-like outline, and at other parts by curving lines. Some of the panels have a partial border of flowers. The panels are ornamented with conventional 30 flower and leaf forms and geometrical ornaments of varied character. One panel has prominently placed at its center a group of conventional flower or leaf forms, partly scroll-shaped in character, supported on stems. 35

What I claim as new, and desire to secure by Letters Patent, is—

The design for carpets, consisting of the design substantially as shown.

ARTHUR L. HALLIDAY.
